CIRCULAR BOOMERANG

William G. Sheard, 29295 Lansing Drive,
Westlake, Ohio 44145

Filed May 8, 1970, Ser. No. 22,884

Term of patent 14 years

Int. Cl. D21—02

U.S. Cl. D34—15

FIG. 1 is an enlarged isometric view of the circular boomerang embodying my new design.

FIG. 2 is a top plan view of said boomerang.

FIG. 3 is a side elevation of said boomerang and,

FIG. 4 is an arcuate cross-sectional view taken along line 4—4 of FIG. 2.

I claim:

The ornamental design for a circular boomerang, as shown.
